WELL DRILLING APPARATUS

William Warren Spacek, Richmond, Tex.

Application July 18, 1949, Serial No. 105,351

8 Claims. (Cl. 255—19)

1

This invention relates to a method of drilling wells, as oil or water wells, and to a bit assembly structure designed therefor so that the bits thereof may be changed when desired by moving the bit assembly up and down the drill stem without having to remove the drill stem from the well.

It is an object of this invention to provide a drilling method and a bit assembly structure therefor which may be moved up and down the drill stem employed in the rotary method of drilling wells, so that the bits of the bit assembly may be changed without the necessity of having to remove the drill stem from the well.

It is a further object of this invention to provide a drill bit assembly of this class adapted to drill an oval hole.

It is also an object of this invention to provide a drill bit assembly of this class which is adapted to drill a round hole.

It is a further object of this invention to provide drill bit assemblies of this class which are adapted to be operated on the drill stem without interfering with the fluid circulation therethrough.

It is also an object of this invention to provide a method of drilling and a drill bit assembly structure therefor which requires a much lighter rig for the ordinary handling thereof than is required in present day conventional drilling methods.

It is another object of this invention to provide a drilling method and a drill bit structure therefor which is designed to save the great amount of labor now expended on conventional rigs which require that the whole drill stem be removed from the well every time the bit is to be changed.

It is yet another object of this invention to provide a drill bit structure of this class designed to eliminate the drill stem back lash now encountered in conventional equipment.

It is yet a further object of this invention to provide a structure of this class which is better adapted than conventional structures to permit the quick and easy taking of cores, and running of other essential tests.

It is another object of this invention to provide a drill bit structure of this class having a transmission included therewith adapted to deliver more power to the bits when driven by a smaller size drill stem than the drill stem required for the delivery of the same power by conventional equipment.

Other and further objects will be obvious when the specification is considered in connection with the drawings, in which:

Fig. 1 is a sectional elevation through one modi-

2

fication of the bit assembly and part of the drill stem;

Fig. 2 is a sectional plan view taken along line 2—2 of Fig. 1;

Fig. 3 is a sectional plan view taken along line 3—3 of Fig. 1;

Fig. 4 is a sectional bottom view taken along line 4—4 of Fig. 1;

Fig. 5 is a side elevation taken along line 5—5 of Fig. 4;

Fig. 6 is a sectional elevation showing the lowering or landing spear;

Fig. 7 is a sectional elevation showing the elevating spear;

Fig. 8 is a side elevation showing the reamer construction;

Fig. 9 is a bottom view taken along line 9—9 of Fig. 1;

Fig. 10 is a diagrammatical view showing the substantial contour of the hole cut by the bits of Fig. 1;

Fig. 11 is a sectional elevation showing a second modification of the drill bit assembly and part of the drill collar structure of this invention;

Fig. 12 is a side elevation taken along line 12—12 of Fig. 11;

Fig. 13 is a diagrammatical view showing the contours of the holes cut by the bits of Fig. 11; and

Fig. 14 is a sectional elevation taken along line 14—14 of Fig. 11 showing the connection of the drill collar on which the bit assembly is mounted to the tool joint and drill stem section thereabove.

In the conventional manner of drilling wells by the rotary method the drill stem employed usually consists of pipe sections connected by tool joints of larger diameter than the pipe and near the lower end of the drill stem a drill collar or a number of such collars is added. These collars being of the diameter of the tool bits thereabove or larger.

Finally the bit which drills the hole which is of substantially larger diameter than the drill collar is installed on the end of the drill collar. The whole drill stem is of tubular construction so that fluid may be picked up from the mud pit at the top of the well, circulated downwardly therethrough and out through the bit from where it passes upwardly through the annular space between the walls of the bore which the bit has drilled and the drill stem and is circulated outwardly from the top of the well to the mud pit.

With conventional equipment when the bit becomes dulled as occurs periodically due to the hardened earth formations through which it must

55

drill, it becomes necessary to change the bit. This is accomplished by the laborious process of withdrawing all of the drill stem from the well section by section and then replacing it section by section and more time is expended in making such changes, termed "trips" into and out of the well than in any other one drilling operation.

With the apparatus of this invention the necessity of removing the drill stem every time the bit has to be changed is eliminated by providing a bit assembly which may be pulled up over the drill stem and slid back downwardly thereover; the drill stem remaining all the time in the well.

In the form of the invention disclosed in Fig. 1 the drill stem 1 is comprised of "flush joint" type pipe which is of a uniform outer diameter throughout the length thereof and which has the joints between sections extended inwardly. The lower section 2 of this drill stem need be modified in only three small particulars to adapt it for use with the bit carrier assembly 3. Such adaptation consists in providing the keyway indentation or lock port 4 therein; providing the annular slotted ring 5 which is rigidly connected to the drill stem exterior near the bottom thereof, and in providing the nozzles 6 at the rounded lower stem end through which the mud or circulating fluid is discharged.

The bit carrier assembly 3 includes an inner element which may be termed the transmission, or transmission assembly 7, which is enclosed and journaled in the housing 8. The central member of the transmission is the power tube 9 which is of an inner diameter to slide over or have a slip fit with the drill stem 2 and which has thereon the spur gear 11, the rings 15 and 16 mounted thereon to rotate in the bearings 17 and 18 respectively of the housing 8 and at the lowest point of the power tube the lock 19 is provided to fit in the slot 21 of the ring 5 on the drill stem 2; the power tube being beveled at 22 to mate with the bevel 23 on the ring 5.

The drive sleeve 10 fits over the power tube 9 and has thereon the spur gears 12 and 13 and the bevel gear 14. This sleeve is journaled in bearings 36 and 37 of the housing 8.

The power tube 9 terminates upwardly in a cylindrical head 24 which has the ring 28 thereon to rotate in the bearing member 29 of the housing 8. A sleeve or collar member 26, which may be a composite element as shown or optionally a casting, is adapted to slide between the head 24 and the power tube 9. This member has the stop ring 25 on the cylinder 27 thereof to lodge against the shoulder 30 when the member 26 is in upper position. A plunger ring 31 is mounted to slide within the annular projection 46 of the member 26 and this ring 31 cooperates with the spearhead or spear engaging shouldered formation 33 of the member 26, as will be hereinafter described, to release the bit assembly 3 after it has been lowered into the well. A radially projectible key or lock 34 is brought into engagement with the power tube 9 by means of the spring 35. When the collar or tubular member 26 is in lower position the skirt extension or cylinder 27 thereof forces the lock 34 into the lock port or keyway 4 of the drill stem 1 to lock the power tube 9 and drill stem together to prevent any relative longitudinal movement, and when the member 26 is in upper position the lock 34 is urged outwardly by the spring 35 to disengage these two elements.

The spur gear 11 on the power tube 9 meshes

5 with the spur gear 39 on the shaft 41 which is journaled within the bearings 42 and 43 of the housing 8 and which has the spur pinion 44 on the end thereof. This spur pinion 44, in turn, meshes with the spur gear 45 on the shaft 46, which is journaled in the bearings 47 and 48 of the housing 8, and which has the spur pinion 49 on the end thereof to mesh with the spur gear 12 on the drive sleeve 10.

10 The spur gear 13 on the drive sleeve 10 drives the pinion 52 at the top of the bit shaft 53 and through the idler 54 it also drives the pinion 55 at the top of the bit shaft 56 with the result that, as shown in Fig. 9, the bits 57 and 58 rotate in opposite directions and in timed relationship so as not to interfere in operation.

20 Bearings 60, 61, and 62 are provided in the housing 8 for the bit shaft 56 and bearings 63, 64, and 65 are provided therein for the bit shaft 53. The seals 66 and 67 are also provided within the housing 8 to seal around the power tube 9 near the top and bottom thereof respectively.

25 The bevel gear 14 meshes with bevel pinions 10 and 71 and the shafts 72 thereof are journaled in the bearings 50 of the housing 8 and have mounted thereon the reamers 73 and 74 as shown in Fig. 4. These reamers, shown in side elevation in Figs. 4 and 8 and in plan in Fig. 5, each comprise four radial arms spaced 90° apart. Co-operating with each reamer is a cleaner 75 also comprising four radial arms, journaled for rotation on the housing 8 with the arms thereof in mesh with the reamer arms so as to extend into and move through the spaces between the reamer arms for pushing out and keeping down accumulations of material reamed away from the bore wall. The cleaners 75 do not engage the bore wall, and therefore are of lesser height transversely of the carrier than are the reamers 73, as clearly shown in Fig. 8.

30 As shown in Fig. 2 the housing 8 is of substantially oval cross-section and in addition to serving as a housing or journal member, is itself a guide means, and has the fins or guides 105 thereon; there being of necessity an enlargement 106 to permit the installation of the necessary transmission elements in the housing. As shown in Fig. 3 the cross-section is modified from that of Fig. 2 to permit the installation of the reamers 73 and 74 and reamer cleaners 75 on the housing.

35 As shown in Fig. 10 the bit 37 cuts a circular hole 110 and the bit 58 cuts a circular hole 111, there being an overlapping area 112 common to both bit holes. The reamers 73 and 74 cut out the formation sections 113 and 114 respectively and thereby round out the oval contour of the hole down through which must pass the housing 8 with the guides 105 thereon.

40 A spear or suspension coupling 80 is provided as shown in Fig. 6 which has a body 81 consisting of a central tube 82 and an outer housing 83 which is connected to the tube as by the plates 84 at the top thereof. These plates have holes 85 therein to receive lines 86 by which the suspension coupling or spear 80 may be lowered or raised over the drill stem 1. Spear arms 87 are pivotally connected at 88 to the housing 83 and slots 89 are provided in the housing so that the arms 87 may be moved outwardly therethrough. Normally the arms 87 are urged inwardly by springs 91 which are attached at 92 to the tube 82 and at 103 to the arms. This type of spear is termed a landing or lowering spear and each arm 87 has a barbed point 93 thereon 45 of triangular cross-section which is adapted to

have the barb 94 thereof fit under the top 95 of the spear head 33 of the bit assembly 3 when the bit assembly 3 is lowered into the well. The hypotenuse face 96 of the barbed point is in contact with the hypotenuse face 97 of the plunger ring 31 when the bit assembly 3 is being lowered. When the bit assembly 3 comes into contact with the ring 5 at the bottom of the drill stem, the housing 8 and power tube 9 are stopped, then when the spear 80 is further lowered, the 10 plunger ring legs 90 contact the housing top 100 and the plunger ring 31 is moved upwardly to force the arms 81 outwardly against the inward urging of the springs 91, and this releases the spear 80 from the spear head 33 so that the spear may be slid upwardly over the drill stem to the top of the well.

When it is desired to raise the bit assembly from the well a spear 104 is provided which is essentially like the spear 80 with the exception that the spear points 101 thereof are of a cross-section to permit the barbs 94 thereof to engage under the top 95 of the spear head 33 without ever coming in contact with the plunger ring 31, even when the member 26 is in its lowest position.

When the bit assembly 3 has been lowered until it contacts the ring 5 of the drill stem the lock 34 on the power tube 9 is not necessarily brought into engagement with the lock port 4 in the drill stem but is confined between the cylinder 27 and the power tube 9. Also, the lock 19 of the power tube 9 is not necessarily in engagement with the slot 21, as shown in Fig. 1, but may be at some point along the beveled surface 23 of the ring 5. It then becomes necessary to apply a slight amount of rotation to the drill stem 1 to move the lock 19 into engagement with the slot 21 and this also brings the lock 34 within the lock port 4.

The modified form of the bit carrier as shown in Figs. 11-14, is designed to eliminate the gearing required in the modification hereinabove disclosed and this elimination of gearing permits the central element or power tube 120 to be constructed of a larger diameter tube than the power tube 9 disclosed in Fig. 1. Such a power tube 120 must be of a size to slide over and have a slide fit to the drill stem 121 and the tool joints 122 which connect the drill stem sections, and also such a power tube 120 must be constructed of a diameter to slide over and have a slide fit to the drill collar 123. This drill collar 123 terminates in the fluid outlet element 124 which has the fluid ports 125 therein, and which also has the ring 126 corresponding to the ring 5 on the drill collar 123. The power tube 120 is brought into locked engagement with the drill collar 123 in the same manner as the power tube 9 is locked to the drill stem 1.

The construction of the spear head or releasable formation 33 and the upper part of the housing 128 is similar to the construction of the corresponding members described hereinabove and shown in Fig. 1 and the same reference numerals are assigned thereto. The housing 128, having no gearing therein, has only to provide the bearings 131 and 132 in which the power tube rings 133 and 134 may rotate respectively. The rings 133 and 134 are fixed to the tube 120, and the tube housing assembly constitutes the carrier assembly for the bit unit.

With this modification an adapter 135 is rigidly fixed to the power tube 120 and the bit socket 136 is threaded thereon. Bits 137 and 138 are formed integrally with the bit socket and in 75

drilling cut out and annular space 140 defined by the outer diameter 141 of bits 137 and 138 and the diameter 143 of the points 144 of the slotted bits 145. As shown in Fig. 11 these slotted bits 145 are pivotally mounted on the bit socket 136 and the angle thereof is set by means of the screws 147. As shown in Fig. 12, the slots 151 in each slotted bit 145 are of a size to permit the bits 137 and 138 to be pivoted therethrough.

This second modification of my invention, in not having the transmission of the first modification, does not eliminate back lash, and is limited to rotate at the same speed that the drill stem is rotated, however it has the advantages of being adapted for use on the conventional drill stem in which the pipe sections thereof are made up by the use of conventional tool joints 122 and therefore a stronger type of drill stem may be employed than the "flush joint" type of drill stem required by the first modification described hereinabove. The elimination of the transmission permits the use of a smaller housing 128 and therefore a smaller bit construction may be employed, so that less power is required 20 to drive such bit construction through a stronger drill stem.

Obviously the guides or fins 105 shown rigidly connected to the guide means or housing 128 in Fig. 11, serve the same purpose as the guides 30 105 shown in Fig. 1, that is, these guides rotate with the housing 128 as it rotates through frictional engagement with the well bore, and thereby tend to achieve and maintain a clean, enlarged, straight bore, as they follow downwardly 35 after the bits, as the bore is drilled thereby.

It is herein pointed out that whereas bits of a specific configuration, as those of the bits 57 and 58, have been shown, this invention is not limited to bits of this type alone but any type 40 of conventional bit or modification thereof may be employed with the apparatus of this invention and results may be accomplished thereby comparable to the results which can be accomplished by the structures disclosed.

It is also pointed out that whereas the word 45 "transmission" has been used generally to include all the elements interposed between the drill stem and the bits and whereas the term "power tube" has been limited to a specific structure as has been the term "drive sleeve," these terms may be employed interchangeably to designate the means by which the drill stem transmits its rotational force to the bits.

The structures disclosed hereinabove are not 50 the only structures adapted for employment in an apparatus which will enable bits to be changed without removing the drill stem from a well and this invention broadly lays claim to any structures other than those disclosed which are adaptable to work within the broad method to which the apparatus hereinabove described has an application.

Broadly this invention considers a drill stem and bit assembly therefor and a method of drilling 55 which does not require the removal of the drill stem in order to change the drilling bits employed thereon.

What is claimed is:

1. In a drill stem and bit assembly employed in the rotary method of drilling wells, the combination of, a bit assembly adapted to be slid over 60 said drill stem, said bit assembly including, a housing and a drive ratio modifying a transmission journaled for rotation in the housing in offset relation with the drill stem, bit means

driven by said transmission for drilling a hole, and means for releaseably locking said transmission to said drill stem for drive therefrom releaseably.

2. In a drill stem and bit assembly employed in the rotary method of drilling wells, the combination of, a bit assembly including, a housing and a speed changing transmission journaled for rotation therein, said transmission including a power tube adapted to be slid over said drill stem, bit means driven by said transmission for drilling a hole, means for locking said transmission to said drill stem for rotation therewith.

3. In a drill stem and bit assembly employed in the rotary method of drilling wells, the combination of, a bit assembly adapted to be slid over the drill stem, said bit assembly including, a change speed transmission, a pair of bits substantially equally and diametrically spaced apart from the axis of said drill stem and each bit being of larger radial dimension than the radial distance from bit axis to stem axis, said bits being connected to the lower end of said transmission one to follow the other over the common transverse area swept by both in rotation, a pair of reamers substantially diametrically opposed across said stem axis above and at substantially right angles to said bits and connected to be driven by said transmission to traverse areas to complete the total cross-sectional area boundary traversed by said bits and said reamers as a substantial oval, a housing surrounding said transmission and to provide the frictional support in which said transmission may rotate, and means to establish a driving engagement between said drill stem and said transmission.

4. Well drilling equipment, including a rotary drill stem having a keyway near its lower end, a drill bit carrier assembly sleeved on said stem by a slip fit for lowering and raising the carrier while the stem remains in the well bore and comprised of an outer guide and bit centralizing tube and an inner bit supporting tube and rotary bearings spacing said tubes and accommodating their relative rotation, a radially projectible key mounted on the inner tube for co-operation with said keyway to releaseably lock the stem and inner tube in drive relation, an axially adjustable collar engageable with said key to control its projection into and out of the keyway, and a formation on said collar for releasable connection with a suspension coupling for lowering and raising the drill bit carrier assembly.

5. Well drilling equipment, including a drill stem, a bit carrier having a slip fit on the stem in the well bore, without displacement of the drill stem, said bit carrier including a central stem driven member, a well bore engaging and bit centralizing spacer rotatably locating the driven member sleeved on the stem, means releaseably drive connecting the driven member and a driving stem comprising a keyway in one and a

5 radially projectible key in the other, and a key actuating shoe shiftable axially of the driven member to control the projection and retraction of the key into and out of drive transmitting reception in said keyway.

6. Well drilling equipment, including a drill stem, a bit carrying sleeve having a slip fit on the stem for raising and lowering the sleeve while the stem remains in the well bore, a spear engaging head having limited axial travel on said bit carrying sleeve, a key for drive coupling the sleeve with the stem and operatively related to said head for uncoupling the drive when the head is raised relative to the sleeve and for coupling the drive when the head is lowered relative to said sleeve.

7. In a well drilling bit carrier for application to and removal from a drill string while the string remains in a well bore, a bit mounting sleeve 20 arranged for a slip fit on the drill string, a spear engaging head surrounding the top of said sleeve and having limited adjustment axially thereof from a raised to a lowered position relative to said sleeve, and a spring mounted retractable key carried by the sleeve in the path of said head so as to be locked in drive coupled relation with the drill string when the head is lowered on the sleeve and to be sprung out of drive coupled relation when the head is adjusted to its upper limit.

8. In a well drilling bit carrier to be slip fitted to a drill string for raising and lowering the carrier without raising and lowering the drill string, a driven tube, a spear engaging head telescoped on the upper end of the tube, limit stops 35 on the head and tube for suspension engagement when the head is raised to its upper limit, a spring retracted drive key carried by the tube in the downward path of said head for projection by the head into drive coupling relation with the 40 drill string.
